COIL MOUNTING

Robert T. Thompson, Oak Park, Ill., assignor to
 Zenith Radio Corporation, a corporation of
 Illinois

Application December 31, 1943, Serial No. 516,361

8 Claims. (Cl. 171—777)

1

This invention relates to the construction of an impedance or transformer and mounting therefor.

In radio circuits having fixed transmission channels, for example, the intermediate frequency channel of a superheterodyne receiver, it is desirable to have the transformers for such channels of simple inexpensive construction allowing ease of manufacture and allowing ease of adjustment in operation of such radio circuits.

A radio transformer requires two windings interlinked with magnetic flux. An impedance element requires but one winding. In the manufacture of radio equipment which requires both transformers and impedance elements, it is desirable to make a winding for use either as an impedance element or for use as one element of a transformer. That is, the winding should be interchangeable for use either as an impedance element or as one element of a transformer.

An object of the present invention is to provide a new and improved transformer construction.

A further object of the present invention is to provide a new and improved winding for use either as one element of a transformer or as one impedance element.

The features of the present invention which are believed to be novel are set forth with particularity in the appended claims. This invention itself, both as to its organization and manner of operation, together with further objects and advantages thereof, may best be understood by reference to the following description taken in connection with the accompanying drawing in which:

Figure 1 is a sectional view of apparatus embodying the present invention, taken substantially on line 1—1 of Fig. 2 with certain elements disengaged;

Fig. 2 is a plan view of a radio frequency transformer construction embodying this invention with the top plate of a shield can removed;

Fig. 3 is a view in perspective, partly in section, of the radio frequency transformer construction shown in Fig. 2;

Fig. 4 shows one of the elements embodying this invention employed as an impedance element, and

Fig. 5 shows another construction embodying the present invention.

The windings 10 and 11 comprising the windings of an adjustable radio frequency transformer are wound respectively on tubular members 12 and 13 of insulating material. Tubular member

2

12 has an internally tapped screw threaded portion 14 for adjustably holding a cooperating screw-threaded powdered iron core member 16 and for receiving a cooperating threaded portion 17 of member 13. Tubular member 13 has, in addition to the screw-threaded projection 17, a threaded internal portion 19 for adjustably holding a powdered iron threaded core member 21.

The members 12 and 13 are joined to one another and mounted on a supporting member 24 by passing the threaded projection 17 of member 13 through an aperture 25 in member 24 and screwing such projection 17 into the cooperating threaded portion 14 of member 12.

In a preferred form of the invention, the coils 10 and 11 are permanently wound on their respective members 12 and 13 and the spacing between such coils may be altered either by providing supporting members 24 of various thicknesses or by providing shims or spacers 27 between the supporting member 24 and shoulder 29 of member 13.

The magnetic coupling between coils 10 and 11 is not only varied by varying their physical spacing but is varied also by moving either one of the powdered iron core members 16 or 21 in their respective supporting members 12 and 13. This particular feature allows ease of adjustment of coupling and tuning when the windings 10 and 11, respectively, form elements of a tuned primary winding and tuned secondary winding in an intermediate frequency transformer in a superheterodyne radio receiver.

The supporting member 24 preferably comprises a flat metal or insulating sheet supported in a rectangular or square metal shielding box 30 with the sheet dimensions such that its length as shown in Fig. 2 corresponds to that of a diagonal of the rectangular box 30. Where the two coils are intended to be magnetically coupled, of course, the sheet 24 is of insulating material.

Where the supporting member 24 is of metal, the winding 10 is electrostatically shielded from the winding 11, and the two windings may be used as independent impedances not coupled with each other.

In the arrangement shown in Fig. 2, the supporting member 24 carrying adjustable transformer windings 10 and 11 is easily inserted into or removed from the rectangularly shaped shielding box 30 within which it is held by cooperation of the opposite edges of supporting member 24 in diagonally opposite corners of box 30.

Holes 34 and 35 in box 30 aligned with the axis of the members 16 and 21 allow passage of

an adjusting tool, for example, a screwdriver, arranged to enter grooves 36 and 37 whereby the position of members 16 and 21 may be adjusted or varied by manipulating such screwdriver.

The leads of coils 10 and 11 are connected respectively to binding posts 39, 40 and 41, 42 insulated from each other and mounted on the supporting member 24. Such an arrangement allows the composite transformer to be removed from its supporting shield can 30 by removing the lid 44 and lifting the supporting member 24 out of such box. If desired, lid 44 may be permanently or semipermanently fastened in place on box 30 by soldering or the like, it being understood that adjustments may be made on the connected transformer by passing a screwdriver or the like through apertures 34 or 35 in box 30 and turning either one of the core members 16 or 21.

Fig. 4 shows one of the elements of the transformer shown in Figs. 1 to 3 used as an impedance device. Corresponding parts in the different figures have identical reference numerals. In Fig. 4, the cylindrical coil holder 13 having coil 11 wound thereon is fastened to the chassis of a radio receiver or base member 32 by screwing the screw-threaded projection 17 into a cooperating tapped screw threaded opening 33 in base member 32.

The inductance of coil 11 in Fig. 4 is altered by adjusting the position of powdered iron core member 21 in its cooperating screw-threaded portion 19 in member 13. The coil 11 may form one element of a tuned circuit whose tuning may be effected by varying the position of powdered iron core member 21. Also in one embodiment of my invention, coil 11 may serve as a choke coil in which case the member 21 is preferably positioned as far as possible within the hollow portion of coil 11.

In Fig. 5, the coil holder 13 having mounted thereon coil 11 is fastened to fastening member 24 by passing the threaded projection 17 through the aperture 25 in supporting member 24 and threading a nut 45 on threaded projection 17. The leads of coil 11 are connected to binding posts or terminals 41 and 42 which are insulated electrically from each other and which extend to the opposite side of member 24 so that a fixed condenser 48 of conventional shape and construction may have its opposite leads connected, as for example, by solder, to such terminals 41 and 42. The position of the powdered iron core member 21 threaded in coil holder 13 may be adjusted by inserting a screwdriver through aperture 35 in metal can 30 and then turning such core member with the screwdriver to adjust the resonant frequency of the resulting tuned circuit.

In Fig. 5, the coil 11 and shunt connected condenser 48 form an adjustable tuned circuit which may be employed in a radio circuit as a "wave trap" or, for example, as a tuned input or output circuit for an electron discharge device.

In the preferred embodiment of my invention, the core members 16 and 21 are screw-threadedly mounted in their insulating supporting members 12 and 13, respectively. It is understood, however, that other means may be used to hold the core members adjustably in their respective supporting members. For example, such means may comprise a frictional engagement between each of the core members and its supporting member.

Furthermore, in the preferred embodiment of my invention the supporting member 24 comprises a relatively thin sheet of insulating or me-

tallic material held in diagonally opposite corners of a box or shield can.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. In a mounting for a transformer, a metal box, a first winding, a winding holder having a screw-threaded projection and having a tapped inner portion, an adjustable core member in said coil holder, a supporting sheet having an aperture through which said projection extends, a second winding, a second winding holder having a tapped portion arranged to receive said screw-threaded projection with said supporting sheet clamped between the two coil holders, an adjustable core member on said second coil holder, whereby said first winding, second winding and said supporting sheet may be moved as a unit apart from said box, said metal box having oppositely disposed corners receiving snugly the edges of said supporting sheet.

2. In a mounting for a transformer, a box, a first winding, a winding holder having a screw-threaded projection, a supporting sheet having an aperture for said projection, a second winding, a second winding holder having a tapped portion arranged to receive said second screw-threaded projection with said support sheet clamped between the two coil holders, whereby said first winding, second winding and supporting sheet may be moved as a unit apart from said box, said box having oppositely disposed corners receiving snugly the edges of said supporting sheet.

3. In combination, a shield box, a coil, a coil support having a screw-threaded projection, a supporting sheet having an aperture for said projection, a second coil, a coil support for said second coil having a tapped inner portion for engagement with said projection with said supporting sheet between the two coil supports, an adjustable core member mounted in said tapped inner portion, terminals for said coils mounted on said supporting sheet, whereby said coil, second coils and supporting sheet may be moved as a unit apart from said shield box, said shield box having oppositely disposed corners receiving snugly said supporting sheet.

4. In a mounting for a transformer, a first winding, a first winding holder having a projection and having a tapped inner portion, an adjustable core member having screw threads thereon in said tapped inner portion, a second winding, a second winding holder having a hollow inner portion receiving said projection of said first holder, said second core holder having a tapped inner portion, and an adjustable core member in said tapped inner portion of said second core holder.

5. In combination, a coil, a coil support having a screw-threaded projection, a supporting sheet having an aperture for said projection, a second coil, a coil support for said second coil having a tapped inner portion for engagement with said projection with said supporting sheet clamped between the two coil supports, an adjustable core member mounted in said tapped inner portion, and terminals for said coils mounted on said supporting sheet.

6. A shielded impedance comprising a shield box of rectangular cross section having oppositely disposed corners, a rectangular supporting sheet fitted snugly in said box between said corners and having an aperture intermediate said corners, a coil form of insulating material, a coil wound on said form, and means for fastening one end of said form in said aperture, said means including screw threads in said one end of said form.

7. A shielded transformer comprising a shield box of rectangular cross section having oppositely disposed corners, a rectangular supporting sheet of insulating material fitted snugly in said box between said corners and having an aperture intermediate said corners, a pair of coil forms of insulating material, a coil wound on each of said forms, and means for fastening said forms through said aperture with said coils in coaxial alignment, said means including screw threads in adjacent ends of said forms.

8. A shielded transformer comprising a shield box of rectangular cross section having oppositely disposed corners, a rectangular supporting sheet of insulating material fitted snugly in said box between said corners, and having an aperture intermediate said corners, a pair of hollow cylindrical coil forms of insulating material, a

coil wound on each of said forms coaxially therewith, a powdered iron core adjustably supported within each of said forms, and means for fastening said forms through said aperture with said coils and forms in coaxial alignment, said means including screw threads in adjacent ends of said forms.
